Inventor

Frederick L Sawyer

By his Attorney C. Campbell Hender

UNITED STATES PATENT OFFICE.

FREDERICK L. SAWYER, OF NEW YORK, N. Y., ASSIGNOR OF ONE-HALF TO CHRISTIAN BERGER, OF BROOKLYN, NEW YORK.

PENCIL.

1,406,585.

Specification of Letters Patent. Patented Feb. 14, 1922.

Application filed March 23, 1920. Serial No. 368,113.

To all whom it may concern:

Be it known that I, FREDERICK L. SAWYER, a citizen of the United States, and resident of New York, in the county of New York and State of New York, have invented certain new and useful Improvements in a Pencil, of which the following is a specification.

This invention relates to pencils of the magazine and self-feeding type.

10 Magazine and self-feeding pencils made of metal are already known and in most forms the pencil must be disassembled to insert a new lead from the magazine. Such forms have had an unsatisfactory writing balance by reason of the improper distribution of mass due to the multiplicity of parts of the feed and magazine.

One of the objects of this invention is to provide a pencil of few parts wherein the 20 lead is fed by a resilient ejector a predetermined amount by pressing the pencil vertically upon the writing material and releasing the pressure.

Another object is to provide a self-feeding 25 pencil that can be reloaded from the magazine by gravity or the magazine charged without disassembly.

Still another object is to provide a pencil that may be carried flat in a vest pocket or 30 purse without injury to the pocket and one which will be of convenient length for writing when in use.

A further object of this invention is to provide a pencil with the proper writing balance wherein the weight is concentrated 35 near the point.

Other objects will appear more fully hereinafter.

Referring to the drawings:

40 Figure I is a longitudinal sectional view of a pencil embodying the principles of my invention.

Figure II is a longitudinal sectional view with the sheath in reloading position.

45 Figure III is an enlarged cross sectional view of Figure I along the line 3, 3.

Figure IV is an enlarged cross sectional view of Figure I looking in the direction of the arrows along the line 4, 4.

Figure V is a longitudinal sectional view 50 of a pencil having a modified form of magazine.

Figure VI is an enlarged sectional view looking in the direction of the arrows along the line 6, 6.

55 The pencil is composed of but four parts, a barrel 1, a sheath 2 for the lead, a spring 4, and a cap 3.

The barrel 1 is slightly tapered exteriorly at 20, 21, near both ends, to frictionally hold 60 cap 3 when it is placed thereon. Within barrel 1 is a cylindrical chamber 15, closed at 16 and open at the other end. Sheath 2 has a central bore 10 for the leads 11 and operates within chamber 15. One end of 65 spring 4 forms a lead ejector 5 within bore 10 of sheath 2 and the other end forms a stop 6 to prevent the insertion of the sheath 2 too far into barrel 1. Stop 6 is an open coil and hence frictionally holds the spring 70 4 in its position in the barrel chamber 15. Sheath 2 carries pin 8 operating in channel 7 to limit the withdrawal of the sheath 2 from the barrel. Magazine 9 is formed in sheath 2 by cutting out a V shaped chamber 75 communicating with the bore 10. Cap 3 is a hollow cylinder and has a plug 13 frictionally held in one end. Plug 13 is adapted to hold eraser 14 in any suitable manner capable of replacement such as frictionally 80 or threaded therein. Plug 13 can be reversed in cap 3 to keep the eraser 14 clean.

To cause the lead to feed in case of breakage or wear the pencil is held vertically by the barrel 1 and the end 19 is pressed down 85 upon the paper causing sheath 2, leads 11 and spring 4 to be forced back into the barrel. Upon relieving the pressure the sheath 2 remains in the barrel but the spring 4 expands extruding a portion of the lead. 90

A new lead may be loaded into the bore 10 by withdrawing the sheath 2, holding the pencil horizontal with the channel 7 at the bottom, until the ejector portion 5 of spring 4 is beyond the end of the magazine when 95 a lead will feed into the bore 10 by gravity. The leads in the magazine are visible in the preferred embodiment of my invention,

when reloading the sheath. The sheath 2 is then pushed back into the barrel to operating position. The magazine 9 can be refilled by withdrawing sheath 2 until stopped by pin 8 and inserting the leads in the uncovered magazine.

Various modifications in the shape and design of the magazine might be made and I have shown one such modification in Figures V and VI wherein the magazine 9' is formed by a circular recess 22 in sheath 2' and having a communicating slot 23 with bore 10'. Projection 24 of sheath 2' prevents the leads 11 from being rotated past slot 23. The reloading is accomplished by withdrawing sheath 2' until the end of the ejector 5' is beyond the end of the magazine to cause a lead to drop from the slot 23 into bore 10'. The slot 23 is filled by slightly rotating the pencil. To load magazine 9', sheath 2' is withdrawn until stopped by pin 8', the pencil is then held vertically and the leads 11 are then inserted in recess 22 and are held in the cup formed by the projecting end of barrel 1' and recess 22 until the sheath is pushed back into the barrel to operating position.

The length of the lead in the sheath is immaterial and I contemplate using several lengths since the operation is equally efficient

and it permits of my shortening the length of the pencil.

What I claim is:

1. In a pencil comprising a barrel and a sheath, a spring in said barrel having one end forming a lead ejector and the other end forming a stop for the sheath.
2. In a pencil comprising a barrel and a sheath, a spring in said barrel having one end forming a lead ejector in said sheath and the other end terminating in a coil to bear against the side wall of said barrel to prevent longitudinal displacement of said spring.
3. In a pencil, a barrel, a solid member having a tight sliding frictional fit telescoping in the barrel, a bore in said solid member to hold several lengths of lead, a spring in said barrel having one end forming an ejector in said barrel and the other end bent to form a stop for the solid member, said bent end adapted to frictionally engage the cylindrical wall of the bore of the barrel to prevent longitudinal displacement of said ejector spring.

Signed at Lake Wales, in the county of Polk and State of Florida, this 6th day of March, A. D. 1920.

FREDERICK L. SAWYER.
